Inventor.

Nicholas Downes

United States Patent Office.

NICHOLAS DOWNES, OF SYRACUSE, NEW YORK.

Letters Patent No. 77,179; dated April 28, 1868.

IMPROVEMENT IN STOVE-DRUMS.

The Schedule referred to in these Letters Patent and making part of the same.

TO ALL WHOM IT MAY CONCERN:

Be it known that I, NICHOLAS DOWNES, of Syracuse, in the county of Onondaga, and State of New York, have invented a new and improved Heat-Radiator; and I do hereby declare that the following is a full, clear, and exact description thereof, which will enable those skilled in the art to make and use the same, reference being had to the accompanying drawings forming a part of this specification, in which—

Figure 1 is a vertical section of my invention taken in the line $x\ x$ in fig. 2, and

Figure 2 is a horizontal section of the same, taken in the line $y\ y$ in fig. 1.

Figure 3 is a plan view of a modification.

Similar letters of reference indicate like parts.

In the accompanying drawings, A represents the stove or furnace to which the heat-radiator B is attached. The radiator consists in a chamber or shell, B, through which the hot gases from the stove A are passed before reaching the main flue or pipe C, and this heating-surface is largely increased by flues d d, which run vertically through the chamber B.

The chamber B is provided with the escapes e f, which lead into the main pipe C; the escape e being placed at its upper end, (as shown in fig. 1,) and the escape f at its lower end. The heater or radiator B is usually placed immediately in the rear of the stove A, and connected thereto by a short pipe, g, at its upper end, so that both are employed to heat a single room; but by lengthening out the connecting-pipe g, so as to carry it through a partition-wall, the stove A may be used for heating one room, while the heater B is set off into an adjoining room on the same floor.

But to make the heater more adaptable generally, so that it will accommodate itself to all requirements and conditions, it is provided with a central pipe, I, (fig. 1,) the upper end of which terminates within the chamber B, near its top, while its lower end opens out through the bottom of the chamber, but is closed, by a cap, i, when not in use.

The upper escape e is provided with a damper, h.

Its operation is as follows: When a direct draught is required, the damper h is opened, and the heat from the stove merely passed through the upper end of the heater, but, by closing the damper h, the chamber B is filled with hot gases, which can only escape into the flue C from the bottom of the chamber B, by means of escape f, and by this means the draught from the chamber B is kept up by the colder gases, which settle at the bottom of the chamber. The action is the same when the heater is placed in a room above the stove, as, when the cap i has been removed from pipe I, and used to close pipe g, and the lower end of pipe I connected with the stove, the pipe I discharges the hot gases from the stove into the upper end of the chamber B.

The flues d d have no communication with the inside of the chamber B.

Cold air below the heater is drawn into them, and, becoming heated, flows out at the top.

Fig. 3 shows a modification in the form of the shell B, to allow the heater to occupy less space when used in the same room with the stove A. This modification consists in giving the side next to the stove a concave form, as shown by k k, so that the stove and heater, as a whole, are more compact in form. In the view shown (fig. 1,) the stove A has but one escape, g, but two can be used, (an upper and lower escape, similar to escapes e and f, in the heater,) as ordinarily. But two escape-pipes for the stove are of importance only when the heater is used in a separate room.

This radiator has been used, and found to give a very satisfactory result.

What I claim as my invention, and desire to secure by Letters Patent, is—

The shell B, flues d d, pipes C, e, f, g, I, and damper h, all constructed and arranged as herein shown, and for the purpose described.

NICHOLAS DOWNES.
